UNITED STATES PATENT OFFICE.

EDWARD ERICKSON, OF CLIFTONDALE, AND PETER SJOSTROM, OF MAPLEWOOD,
MASSACHUSETTS.

LIFTING-JACK.

1,207,519.

Specification of Letters Patent.

Patented Dec. 5, 1916.

Application filed February 4, 1916. Serial No. 76,486.

To all whom it may concern:

Be it known that we, EDWARD ERICKSON, a subject of the King of Sweden, and a resident of Cliftondale, in the county of Essex and State of Massachusetts, and PETER SJOSTROM, a subject of the King of Sweden, and a resident of Maplewood, in the county of Middlesex and State of Massachusetts, have invented certain new and useful Improvements in Lifting-Jacks, of which the following is a specification.

This invention relates to lifting jacks, and particularly to devices of this character intended especially for use in connection with motor cars, and it has for its object the provision of a jack so constructed that the lifting operation may be controlled at the end of a lateral arm, thus making it unnecessary for the operator to exert himself by manipulating an oscillating controlling lever as in most of the jacks now in general use.

The invention consists in a standard having a chambered base in which is mounted mechanism for rotating a screw extending through a nut secured to the lower end of a vertically reciprocating lifting member, said rotating mechanism being operated by a rotatable arm extending laterally from said base and inclined upwardly therefrom.

The invention further consists in means for locking the operating arm to the driving mechanism and in means whereby the operating arm may be folded when not in use and rigidly locked when extended.

The invention consists further in means whereby a handle may be confined within the operating arm under normal conditions and moved into a position transversely thereof when it is desired to rotate said operating arm thereby.

The invention further consists in certain novel features of construction and arrangement of parts which will be fully understood by reference to the description of the drawings and to the claims hereinafter given.

Of the drawings: Figure 1 represents an elevation of a jack embodying the principles of the present invention. Fig. 2 represents a vertical section of the body portion of the jack and a part of the rotatable operating member, said figure being drawn to an enlarged scale. Fig. 3 represents a horizontal section of the same, the cutting plane being on line 3-3 on Fig. 1. Fig. 4 represents a section of the lower end of the rotatable

operating member. Fig. 5 represents an elevation of the same. Fig. 6 represents a longitudinal section of the hinge connection between the two parts of the rotatable operating member. Fig. 7 represents a section of the same, the cutting plane being on line 7-7 on Fig. 6. Fig. 8 represents an elevation of the same. Fig. 9 represents a longitudinal section similar to Fig. 6, showing the two parts of the rotatable operating member folded on each other. Fig. 10 represents a longitudinal section of the outer end of the rotatable member. Fig. 11 represents a similar view to be hereinafter described. Fig. 12 represents a similar view showing a portion of the handle in its operating position, and Fig. 13 represents a section of the same on line 13-13 on Fig. 12.

Similar characters designate like parts throughout the several figures of the drawings.

In the drawings, 10 is a base having a standard 11 projecting upwardly therefrom, this standard being provided with a vertical chamber 12 extending longitudinally thereof. In the chamber 12 is positioned a tubular member 13 adapted to be reciprocated therein. To the upper end of the tubular member 13 is secured a support 14, said support having a shank extending into said tubular member 13 and fastened therein by means of the transverse pin 15. Preferably the standard 11 and the tubular member 13 are made rectangular in cross section, as indicated in Fig. 3 of the drawings. By means of this construction the tubular member 13 is prevented from turning about its axis as it reciprocates within the chamber 12. Inserted into the lower end of the tubular member 13 is a nut 16 through which extends the screw member 17 having threads coacting with the threads of said nut 16. To the lower end of the screw 17 is secured a bevel gear 18, the teeth of which mesh with a pinion 19. The gear 18 and pinion 19 are positioned within a chamber 20 within the base 10.

A plate 21 is secured to the lower end of the base 10 by means of the members 22 and nuts 23, said plate 21 closing the open end of said base 10, as indicated in Fig. 2 of the drawings. The base plate 21 has a conical seat 24 therein in which is positioned the conical end 25 of a threaded member 26 extending from the lower end of the screw 17

and threaded thereto in axial alinement therewith. By adjusting the member 26 relatively to the screw 17 the gear 18 may be raised and lowered relatively to the driving pinion 19 in an obvious manner. When the proper adjustment of the gear 18 and the pinion 19 has been made in order to secure the proper mesh of the teeth thereof, said member 26 is locked in its adjusted position 10 by means of the locknut 27.

The hub of the pinion 19 is provided with an annular groove 28 with which engages the pin 29 mounted in the casing 11 and extending transversely thereof. This pin 29 15 prevents longitudinal movement of the pinion 19. The base 10 has extending therefrom a cylindrical boss 30 in which is mounted a cylindrical bushing 31. The hub 32 of the pinion 19 extends into said bushing 31 and is provided with a reduced shank 33 between the wall of which and the inner wall of the bushing 31 is adapted to be inserted 20 the lower end of the tubular operating member 34.

25 The shank 33 is provided with the outwardly extending lug 35 adapted to be positioned in a slot 36 in the end of the member 34 when its lower end has been positioned within the bushing 31. The shank 33 has a 30 transverse opening 37 therein in which is located a spring 38 pressing a ball 39 outwardly. This ball 39 is adapted to enter a depression or recess 40 in the lower end of the member 34 when said end has been 35 positioned within the bushing 31, thus locking said member to the pinion 19 and preventing its accidental displacement therefrom. The cylindrical boss 30 is preferably inclined upwardly as indicated in Figs. 1 40 and 2 of the drawings.

The outer end of the member 34 has secured thereto a block 41 having a projecting ear 42 extending laterally therefrom which ear is pivotally connected by means of the pin 43 with the ears 44 struck from the lower end of the tubular member 45. Adjacent to the pivot pin 43 is an opening 46 extending transversely of the block 41. In this opening 46 are two balls 47 pressed outwardly 45 from each other by means of a spring 48. The ears 44 are provided with recesses or depressions 49 therein with which the balls 47 are adapted to coact to lock the members 34 and 45 in alinement.

55 When it is desired to fold the section 45 upon the section 34, as shown in Fig. 9, the part 45 is moved about the axis of the pivot 43, the balls 47 being moved inwardly 60 against the tension of the spring 46 in so doing. While in this position the ears 44 prevent the accidental displacement of the balls 47. As soon, however, as the part 45 is returned into position in alinement with the part 34, the recesses 49 will be moved into a 65 position opposite to the balls 47 and the

latter will enter the recesses 49 and lock the two parts together and retain said parts in operative position.

While in alinement the parts 34-45 will be turned about their axes and rotate the pinion 19 thereby effecting the rotation of the screw 17, and thus causing the nut 16 with the tubular member 13 connected therewith to be raised or lowered within the chamber 12. The rotation of the members 70 34-45 is effected by means of the handle 50. The handle 50 extends through a transverse opening in the revoluble member 51 mounted in the bifurcated member 52 secured to the outer end of the member 45. 75 This handle 50 is provided with a head 53 at each end thereof and midway between said heads it has an annular groove 54. When the jack is not in operation the handle 50 is pushed through the opening in 80 the revoluble member 51 and until one of its heads bears against said revoluble member, the larger part of said handle being at 85 this time positioned within the tubular member 45, as indicated in Fig. 10 of the drawings.

When it is desired to operate the jack the handle 50 is pulled through the opening in the revoluble member 51 until the opposite head thereof is in contact with the revoluble 90 member 51 and then said revoluble member is turned about its axis until the handle 50 is at right angles to the axis of the rotatable operating members 34-45, and then said handle is moved relatively to the revoluble 100 member 51 until the groove 54 therein is positioned midway of the length of said revoluble member 51, as shown in Figs. 12 and 13 of the drawings. When thus positioned the handle 50 will be locked from accidental movement by means of the spring 105 pressed ball 55 mounted in said revoluble member and coacting with said groove 54. When the handle 50 has been thus positioned the operator may rotate the members 34-45 110 in either direction at will and raise or lower the support 14 as desired. As soon as the use of the jack has been completed the handle 50 is returned into its normal position within the tubular member 45 and the member 34 is disconnected from the operating pinion 19 and the two parts of the operating handle 34-45 are folded into contact with each other about the pivot 43. When the parts are thus disconnected and folded, they 115 120 occupy very little space in the tool box of the car.

By having the operating parts of the screw in the chambered base, greater rigidity is given to the jack when in use. It is also true that by making the tubular member 13 movable lengthwise and the screw 17 movable only about its axis, the lifting member is provided with a substantial bearing surface at all times when in operation. Owing 125 130

to the inclination of the boss 30 and the inclination of the rotatable operating arm 34—45, the jack may be easily operated without any necessity of the operator crawling beneath the motor vehicle. By means of the use of the screw 17 coacting with the nut 16 of the lifting member 13—14, great leverage may be attained by the simple rotation of the operating arm 34—45.

10 It is believed that the operation and many advantages of this invention will be fully understood from the foregoing description.

Having thus described our invention, we claim:

15 1. In a device of the class described, the combination of a standard; a reciprocating tubular member therein; a nut in the lower end thereof; a screw threaded member extending through said nut; a bevel gear secured to the lower end of said threaded member; a bevel pinion meshing therewith; means for rotating said pinion; a base plate secured to the bottom of said standard provided with a conical seat in axial alinement 25 with said threaded member; and a stud adjustably mounted in the end of said threaded member and having a conical end positioned in said seat.

20 2. In a device of the class described, the combination of a standard; a reciprocating tubular member therein; a nut in the lower end thereof; a screw threaded member extending through said nut; a bevel gear secured to the lower end of said threaded member; a bevel pinion meshing therewith; means for rotating said pinion; a base plate secured to the bottom of said standard provided with a conical seat in axial alinement 35 with said threaded member; a stud screwed into the end of said threaded member and having a conical end positioned in said seat; and means for locking said stud in adjusted position.

30 3. In a device of the class described, the combination of a standard having a chambered base and a cylindrical boss extending from said base; lifting mechanism in said base and standard including a revoluble member having a hub mounted in said cylindrical boss and provided with a reduced shank extending outwardly therefrom; a lateral projection from said shank; a spring pressed locking member in said shank adapted to extend beyond the periphery thereof; and a rotatable tubular member provided at one end with a slot to receive said projection and a recess to receive said locking member when said end has been positioned between the periphery of said shank and the wall of 40 said boss.

35 4. In a device of the class described, the combination of a standard having a chambered base and a cylindrical boss extending from said base; lifting mechanism in said base and standard including a revoluble

member having a hub mounted in said cylindrical boss and provided with a reduced shank extending outwardly therefrom; a rotatable member having a cylindrical portion adapted to be positioned between said shank 70 and the inner wall of said boss; and means for locking said rotatable member to said shank.

5. In a device of the class described, the combination of a standard having a chambered base and a cylindrical boss extending from said base; a reciprocating tubular member in said standard; a nut in the lower end of said tubular member; a threaded member extending through said nut; a bevel gear secured to the lower end of said threaded member; a bevel pinion meshing with said gear and provided with a hub mounted in said cylindrical boss; a rotatable member having one end adapted for insertion in 80 the outer end of said boss; and means within said boss for locking said inserted end to the hub of said pinion.

6. In a device of the class described, the combination of a standard having a cylindrical boss extending laterally therefrom; a reciprocating member in said standard; mechanism for reciprocating said member including a revoluble member in said boss; a rotatable member having one end adapted 90 for insertion in said boss; and means within said boss for locking said inserted end to said revoluble member.

7. In a device of the class described, the combination of a standard having a cylindrical boss extending laterally therefrom; a reciprocating member in said standard; mechanism for reciprocating said member including a revoluble member in said boss; a rotatable member having one end adapted 100 for insertion in said boss; means for locking said inserted end to said revoluble member; a bifurcated member at the outer end of said rotatable member; a cylindrical member revolvably mounted in said bifurcated member and having a hole extending transversely therethrough; and a headed handle positioned in said hole and adapted to be moved endwise therein.

8. In a device of the class described, the combination of a standard having a cylindrical boss extending laterally therefrom; a reciprocating member in said standard; mechanism for reciprocating said member including a revoluble member in said boss; a rotatable member having one end adapted 110 for insertion in said boss; means for locking said inserted end to said revoluble member; a bifurcated member at the outer end of said rotatable member; a cylindrical member revolvably mounted in said bifurcated member and having a hole extending transversely therethrough; a headed handle positioned in said hole and adapted to be moved 120 endwise therein, said handle having an an-

nular groove intermediate its ends; and a spring pressed locking device in said cylindrical member adapted to coact with the groove in said handle when in operative position.

9. In a device of the class described, the combination of a standard having a cylindrical boss extending laterally therefrom; lifting mechanism within said standard including a revolute member in said boss; a tubular rotating member having one end adapted for insertion into said boss and to be locked to said revolute member; a block secured to the opposite end and provided with a lateral projection; another tubular rotating member having ears adapted to inclose said projection; a pivot pin extending through said ears and projection; and means for locking said tubular members in alinement.

10. In a device of the class described, the combination of a standard having a cylindrical boss extending laterally therefrom; mechanism within said standard including a revolute member in said boss; a tubular rotating member having one end adapted for insertion into said boss and to be locked to said revolute member; a block secured to the opposite end and provided with a lateral projection and a transverse opening therethrough; two balls in said opening; a spring

between said balls forcing them outwardly; another tubular rotating member having ears adapted to inclose said projection; a pivot pin extending through said ears and projection; and recesses in said ears adapted to coact with said balls to lock said tubular members in alinement.

11. In a device of the class described, the combination of a standard having a cylindrical boss extending laterally therefrom; mechanism within said standard including a revolute member in said boss; a tubular rotating member having one end adapted for insertion into said boss and to be locked to said revolute member; a block secured to the opposite end and provided with a lateral projection; another tubular rotating member having ears adapted to inclose said projection; means for locking said tubular members in alinement; and a handle normally contained within said outer tubular rotating member but adapted to be withdrawn therefrom and disposed transversely thereof.

Signed by us at 4 Post Office Sq., Boston, Mass., this 29th day of January, 1916.

EDWARD ERICKSON.
PETER SJOSTROM.
